US00D959822S

(12) **United States Design Patent** (10) Patent No.: **US D959,822 S**
(45) Date of Patent: ** Aug. 9, 2022

(54) **KEY FOB**

(71) Applicant: **Google LLC**, Mountain View, CA (US)

(72) Inventors: **Rochus Emmanuel Jacob**, San Francisco, CA (US); **Hae rim Jeong**, San Francisco, CA (US)

(73) Assignee: **GOOGLE LLC**, Mountain View, CA (US)

(**) Term: **15 Years**

(21) Appl. No.: **29/787,140**

(22) Filed: **Jun. 4, 2021**

Related U.S. Application Data

(63) Continuation of application No. 29/736,689, filed on Jun. 2, 2020, now Pat. No. Des. 922,760, which is a continuation of application No. 29/609,492, filed on Jun. 30, 2017, now Pat. No. Des. 888,410.

(57) **CLAIM**

The ornamental design for a key fob, as shown and described.

DESCRIPTION

The patent or application file contains at least one figure executed in color. Copies of this patent or patent application publication with color figure(s) will be provided by the Office upon request and payment of the necessary fee. FIG. 1 is a front top perspective view of a key fob showing our new design;

FIG. 2 is a rear bottom perspective view thereof;

FIG. 3 is a front elevational view thereof;

FIG. 4 is a rear elevational view thereof;

FIG. 5 is a left-side elevational view thereof, the right-side elevational view being a mirror image of the left-side elevational view;

FIG. 6 is a top plan view thereof; and,

FIG. 7 is bottom plan view thereof.
